UNITED STATES PATENT OFFICE.

CECIL C. ADAMS, OF LOYALTON, SOUTH DAKOTA.

POST-SHARPENER.

1,356,031.

Specification of Letters Patent. Patented Oct. 19, 1920.

Application filed May 11, 1920. Serial No. 380,678.

To all whom it may concern:

Be it known that I, CECIL C. ADAMS, a citizen of the United States, and a resident of Loyalton, in the county of Edmonds and 5 State of South Dakota, have invented a certain new and useful Post-Sharpener, of which the following is a specification.

The object of my invention is to provide a post sharpener of simple, durable and inexpensive construction, whereby the ends 10 of wooden posts may quickly and readily be sharpened.

It will be understood that in certain localities, the formation of the earth is such, 15 that fence posts are driven into the ground rather than digging a hole and setting them in. My device is so adapted that the end of the post will be sharpened with such accuracy that it will tend to hold the post 20 absolutely vertical, while it is being driven into the ground.

More particularly, it is my object to provide a post sharpener, having cutting rollers thereon for engaging one end of the post, 25 and having a post gripping device for engaging the free end of the post and holding it against rotation or movement in any direction.

Still a further object is to provide a post 30 sharpener, having converging cutting rollers and a guide device placed between the rollers, whereby the end of the post designed to be sharpened may be guided or held in such position, that the sharpened 35 end of the post will be true rather than one-sided.

Still a further object is to provide a device, which has means thereon for engaging one end of the post, and for causing it to 40 automatically feed in between the rollers during the operation of the rollers and the sharpening of the post.

Another object of my invention is to provide power driven cutting rollers and an 45 automatically moving feed mechanism, whereby the feeding mechanism will operate when the cutting rollers are operated, and a clutch device provided, whereby it is possible to render the cutting 50 rollers inoperative, when it is desired to reverse the operation of the feeding mechanism, and cause it to be moved back to its original position.

Still another object is to provide an auto-

matically feeding mechanism and a pair of 55 converging rollers, having a guide device spaced between them, the rollers being adapted to rotate upon their axis, and also to travel around the guide device.

With these and other objects in view, my 60 invention consists in the construction, arrangement and combination of the various parts of the device, whereby the objects contemplated are attained, as hereinafter more fully set forth, pointed out in my claim, 65 and illustrated in the accompanying drawings, in which:

Figure 1 shows a side elevation of my device.

Fig. 2 shows a top view of the same.

Fig. 3 shows a central, sectional view taken on line 3—3 of Fig. 1, showing the gear teeth for causing the cutting rollers to operate, when power is applied to the pulley wheel.

Fig. 4 shows a central, sectional view taken on line 4—4 of Fig. 1, showing the bearings for supporting the front end of the guide device and cutting rollers.

Fig. 5 shows a central, sectional view taken on line 5—5 of Fig. 2, showing the gear connections between the drive shaft and the automatic feeding rod.

Fig. 6 shows a central, sectional view taken on line 6—6 of Fig. 2, showing the 85 entire device cut in section.

Fig. 7 shows an enlarged, sectional view of the converging cutting rollers and the guide device; and

Fig. 8 shows a sectional view through the 90 automatic feeding mechanism, and the post gripping devices.

In the accompanying drawings, I have used the reference numeral 10 to indicate the ordinary base or frame member of my device.

The base or frame member 10 is bolted or rigidly secured to a suitable platform by means of the lag screws 11. Extending upwardly and substantially in alignment with each other are supporting columns 12, 13, and 14.

Slightly spaced above the base or frame 10 and secured to the columns 12 and 13 is the table or platform 15, upon which 105 the automatic feeding device is slidably mounted.

The column 14 is provided with a bear-

ing member 16, which has the upwardly extending fingers 17 and 18. A bracket 19 extends upwardly from the column 14, and is provided near its upper end with a bearing cap 20.

The bracket 19 provides a bearing for the drive shaft 21, which is provided with a pulley wheel 22.

Fixed on the upper end of the column 13 10 is the hollow drum member or casing 23. The drum 23 is provided with a hub 24, in which is the central opening 25.

A shaft 26 extends through the opening 25 of the hub 24, and is provided near its 15 rear end with a clutch member 27. The shaft 21 is also provided near its forward end with a coacting clutch member 28. The clutch member 28 is slidably but non-rotatably fixed on the shaft 21.

20 Extending rearwardly from the drum 23 is the bracket 29. A clutch control lever 30 is pivoted at 31 to the bracket 29. The clutch member 28 is provided with an annular groove 32, in which is received the 25 bifurcated portion 33 of the clutch control lever 30.

The forward end of the shaft 26 is provided with an enlarged head portion 34.

Extending upwardly from the table member 15 30 is the bracket 35, which forms a support or bearing for the guide device 36. A bearing cap 37 extends over the upper end of the bracket 35. The guide device 36 is provided with a central opening 38, which 35 is designed to receive the end of the wooden post, which is designed to be sharpened.

Journaled in the guide device 36 and in the head portion 34 of the shaft 26 are the cutting roller shafts 39 and 40.

40 Rotatably mounted on the shafts 39 and 40 are the cutting rollers 41 and 42. Formed on the device and fixed to the head portion 34 of the shaft 26 are the connecting bars 43.

From the construction of the parts here- 45 tofore described, it will be seen that when power is applied to the pulley wheel 22, and the clutch is in operative position, rotation of the pulley wheel will impart rotation to the shaft 26 and to the guide de- 50 vice 36.

The drum 23 is provided with gear teeth 44. The rear end of the cutting rollers 41 and 42 are provided with gear teeth 45 and 46 respectively. The gear teeth 45 and 46 55 of the cutting rollers 41 and 42 are designed to mesh with the gear teeth 44 of the drum 23.

From the construction of the parts just 60 described, it will be seen that when the guide device is being rotated, the gear teeth 45 and 46, being in mesh with the gear teeth 44, will cause each of the rollers 41 and 42 to rotate upon their axle or shaft 39 and 40 respectively.

65 It will be seen that the cutting rollers

travel around the post and at the same time, the cutting rollers are continuously rotated upon their own shafts.

I will now describe the automatic feed- 70 ing mechanism and the post gripping de- vice.

Fixed on the shaft 21 is the worm wheel 47, which is in mesh with the worm 48. The worm 48 is fixed to the shaft 49. Mounted on the lower end of the shaft 49 75 is a worm wheel 50, which is in mesh with the worm 51.

Journaled in the fingers 17 and 18 of the bearing member 16 is the rod 52. The worm 51 is placed between the fingers 17 and 18 80 of the bearing member 16, and is fixed to the rod 52.

From the construction of the gearings just described, it will be seen that the shaft 21 will impart rotation to the rod 52. 85

Slidably mounted on the table member 15 is the supporting member 53, which is provided with a central screw-threaded opening 54. The table member 15 is provided with overlapping tongues 55, which are de- 90 signed to be received in the grooves 56 of the supporting member 53.

The rod 52 is screw-threaded at 54a near its forward end, and is designed to be received in the screw-threaded opening 54 of 95 the supporting member 53.

It will be noted that rotation of the rod 52 in either direction will cause the supporting member 53 to be moved in either direction. 100

Fixed on the upper surface of the supporting member 53 is what I call a post gripping device 58. The post gripping device 58, comprises the portion 59, which is fixed to the supporting member 53, and a 105 double hinged yoke portion 60. The hinged portions 60 are provided with an overlapping locking portion 61.

The post gripping device is made of resilient material, whereby the parts may be 110 sprung to locking position.

In order to positively lock the post against any rotation whatsoever, when the cutting rollers are operating, I have provided a crank member 62, which is screw-threaded into the fixed member 59 of the gripping device 58. The crank 62 is provided with a sharpened point 63 and a handle 64. When the post is placed in the gripping device, I am then able to absolutely lock it in position by tightening the crank member 62, until the point 63 extends into the wooden post about to be sharpened. 115

In the practical operation of my device, 120 it will be noted that the hinged yoke members 60 are opened and the post is then placed into the opening 38 of the guide device 36, while the other end is permitted to 125 rest in the post gripping device. The crank 130

62 is then tightened, thereby locking the post in proper position.

When power is applied to the pulley wheel 22, and the clutch is in operative position, the cutting rollers will rotate, while the rod 52 will draw the supporting member 53 toward the cutting rollers, and thus cause the post to be automatically fed in between the cutting rollers.

10 After the post has been sharpened, the power is then turned off, and the post gripping device is released, then the post can readily and easily be withdrawn from the opening 38 of the guide device 36.

15 In order to remove the supporting member 53 and to place the gripping device back to its original position, that is the position where it will be when the new post is about to be sharpened, the clutch members will be 20 disengaged, and by reversing the direction of the rotation of the pulley wheel 22 will cause the gripping device to be moved away from the cutting rollers and back to its original or starting position.

25 It will be understood that with my device, posts may be readily and easily sharpened efficiently, so that they may be driven into the ground without much trouble.

30 Another advantage is that I am able to automatically feed the post in between the cutting rollers gradually, so that the effect of the cutting rollers upon the post will not tend to crush it or split it, as would be the 35 case, if the post were suddenly pushed in between the cutting rollers.

By making the cutting rollers travel around the post and at the same time rotate

upon their own shafts, I am able to get a fine even taper on the post, which is very 40 important, when it is desired to use the post for driving it into the ground.

Some changes may be made in the construction and arrangement of my improved device without departing from the real purpose and spirit of my invention, and it is my intention to cover by my claim any modified forms of structure or use of mechanical equivalents, which may be reasonably included within their scope. 50

I claim as my invention:

In a device of the class described a base, having a bearing member thereon, a shaft rotatably mounted therein, a supporting platform on said base, a pair of converging 55 cutting rollers operatively connected with said shaft, a guide device spaced between said cutting rollers and fixed to one end of said shaft, a bearing member for supporting the free end of said guide device, the 60 parts being so arranged that rotation of the shaft will impart rotation to said guide device and rotation of said cutting rollers independent of the rotation of the guide device, a member slidably mounted on said 65 supporting platform, means for moving said last member toward or from the guide device, said means including a rod having a screw threaded portion thereon, said last portion being received in said slidable member and gearing between said shaft and said rod, whereby rotation of said shaft in either direction will impart sliding movement to said member in either direction. 70

Des Moines, Iowa, April 22, 1920.
